Miller Henry & Boykin

ATTORNEY.

UNITED STATES PATENT OFFICE.

MILTON H. SHOENBERG AND LESTER SCHON, OF SAN FRANCISCO, CALIFORNIA; SAID SCHON ASSIGNOR TO SAID SHOENBERG.

FLUID HEATER.

Application filed April 30, 1924, Serial No. 710,003. Renewed February 18, 1926.

Our invention has for its object a simple electric device for heating water or other fluids in any conventional container.

Other objects are means for automatically interrupting the energizing circuit when the heating element becomes too hot, and also means for maintaining the heating element deenergized until it has been plunged into the fluid to be heated, or when withdrawn therefrom.

Other objects are a heating element inclosing an electrical resistance hermetically sealed therein and mounted on a tubular telescoping support in combination with automatic cut-out means interrupting the circuit when the element becomes overheated.

By referring to the accompanying drawings our invention will be made clear.

Fig. 1 is a side view of one form of heater employing our invention.

Fig. 2 is an enlarged fragmentary side view with some of the parts broken away to better show the details of construction.

Fig. 3 is a section of the tubular support and showing in view the supporting arm of the heating element and is taken on the line III—III of Fig. 2.

Fig. 4 is a part cross section and part side view of the heating element with the automatic cut-out means and the electric circuit connections, and also shows the winding of the resistance wire within the heating element.

Fig. 5 is a fragmentary enlarged cross section at right angles to Fig. 4 showing the manner of winding and insulating the resistance element and its mounting within the metallic sheath.

Throughout the figures similar numerals refer to identical parts.

A base plate is shown by the numeral 1 from which rises the standard 2 and within which latter is telescoped the tube 3, the latter carrying an extended arm 4 having a clamp screw and collar at 5, 6, respectively and a releasing pin at 7 normally held in the position shown in Fig. 2 by the spring 8. When the pin 7 is withdrawn the passageway within the standard 2 is cleared and the member 3 then telescopes or falls into the full line position of Fig. 1, at which time

the heating element 9 has fully entered the tumbler or other receptacle 10, and is now in position for heating the water or other fluid 11. When the member 3 falls within 55 the tube 2 due to the withdrawing of the pin 7 the connections 12, 13, engage with the circuit terminals 14, 15, respectively completing the electrical circuit from the energizing connections 16, 17, through the re- 60 sistance 18.

The current now flows through the resistance winding 18 highly heating the sides 19, 20, of the heating element 9 which is shaped to give a large metallic surface exposure and 65 therefore to most readily transmit the heat from the resistance coil 18 to the fluid 11.

Circuit connections to the coil 18 are established in any conventional manner as through the wires 21, 22, to the frictional 70 contacts 23, 24, respectively which co-operate with the connections in the socket 25 energizing wires 26 and thence to the connections 12, 13.

We prefer to mount the lamp 27 in the circuit of the heating element so that when the heating element is being energized the lamp 27 burns. Its manner of connection preferably in parallel, is well known and therefore not shown.

It will now be seen that if the heating element is in operation, the circuit plug 25 be removed from the pins 23, 24, the circuit will be broken. To automatically accomplish this when the heating element 9 becomes overheated, we provide the tube 30 within which is adapted to loosely slide the plug 31. This plug is held in the full line position of Fig. 4 by the wire 32 which is soft soldered within the collar 33 leaving 80 an overhanging tube portion 34 which frictionally engages the pin 35 integral with the plate portions 19, 20, of the heating element, of if preferred a collar or thimble into which the tube end may slide may be substituted.

If the plates 19, 20, rise in temperature due to the energization of the coil 18, the pin 25 and therefore plug 33 become heated and if or when this heat exceeds the melting point of the solder in the collar 33, the spring 36, which is normally under compression,

forces the release of the wire 32 causing the plug 31 to fly upward under the action of the spring. This action pushes the connecting head or circuit plug 25 free from the terminals 23, 24, breaking the circuit and thus causing the automatic interruption of the circuit as above described. A new safety element may be now introduced or the old one repaired and reused by compressing the spring and again soft soldering the wire 32 in the plug 33.

We claim:

1. In a fluid heater a base and a standard thereon said standard comprising a pair of telescoping members, an arm extending from one of said members and overhanging said base, an electrical resistance heating element depending from said arm, energizing connections for said heating element through said members.
2. In a fluid heater a base and a standard thereon said standard comprising a pair of telescoping members, an arm extending from one of said members and overhanging said base, an electrical resistance heating element depending from said arm, energizing connections for said heating element through said members and plugs and sockets for said connections within said members adapted to break the circuit as the members are separated.
3. In a fluid heater a base and a standard thereon said standard comprising a pair of telescoping members, an arm extending from one of said members and overhanging said base, an electrical resistance heating element depending from said arm, energizing connections for said heating element through said members and plugs and sockets for said connections within said members adapted to break the circuit as the members are separated and latch means to normally keep the members separated.
4. In a fluid heater a base and a standard thereon said standard comprising a pair of telescoping members, an arm extending from one of said members and overhanging said base, an electrical resistance heating element depending from said arm, energizing connections for said heating element through said members and plugs and sockets for said connections within said members adapted to break the circuit as the members are separated and latch means to normally keep the members separated, a circuit plug for said heat element and means adapted to release a spring and disconnect the plug and heat element and interrupt the energizing circuit when the element exceeds a predetermined heat.
5. In a fluid heater a base and a standard thereon said standard comprising a pair of telescoping members, an arm extending from one of said members and overhanging said base, an electrical resistance heating ele-

ment depending from said arm, energizing connections for said heating element through said members and plugs and sockets for said connections within said members adapted to break the circuit as the members are separated and latch means to normally keep the members separated, a circuit plug for said heat element and means adapted to disconnect the plug and heat element and interrupt the energizing circuit when the element exceeds a predetermined heat and comprising a spring restrained by a soldered connection which when the solder melts due to excessive heat, is released and separates the plug and the element.

6. Safety means for an electric heating device comprising a spring compressed within a tube, a tie wire soldered to one end of said tube and holding said spring compressed a drive pin at the other end of the tube and circuit breaking means whereby when the solder melts the spring expands forcing the drive pin to actuate the circuit breaking means.

7. In a fluid heater a base and a standard thereon said standard comprising a pair of telescoping members, an arm extending from one of said members and overhanging said base, an electrical resistance heating element depending from said arm, energizing connections for said heating element through said members in combination with safety means comprising a spring compressed within a tube a tie wire soldered to one end of said tube and holding said spring compressed, circuit breaking means and a drive pin at the other end of the tube which actuates the circuit breaking means when the solder melts.

8. In a fluid heater a base and a standard thereon said standard comprising a pair of telescoping members, an arm extending from one of said members and overhanging said base, an electrical resistance heating element depending from said arm, energizing connections for said heating element through said members and plugs and sockets for said connections within said members adapted to break the circuit as the members are separated in combination with safety means comprising a spring compressed within a tube a tie wire soldered to one end of said tube and holding said spring compressed, circuit breaking means and a drive pin at the other end of the tube which actuates the circuit breaking means when the solder melts.

9. In a fluid heater a base and a standard thereon said standard comprising a pair of telescoping members, an arm extending from one of said members and overhanging said base, an electrical resistance heating element depending from said arm, energizing connections for said heating element through said members and plugs and sockets for said

connections within said members adapted to break the circuit as the members are separated and latch means to normally keep the members separated in combination with safety means comprising a spring compressed within a tube a tie wire soldered to one end of said tube and holding said spring com- pressed, circuit breaking means and a drive pin at the other end of the tube which actuates the circuit breaking means when the solder melts. 10
